UNITED STATES PATENT OFFICE.

EMIL SCHÄRER, OF ZURICH, SWITZERLAND.

SCAFFOLDING FOR BUILDINGS AND THE LIKE.

1,113,839.

Specification of Letters Patent. Patented Oct. 13, 1914.

Application filed December 1, 1911. Serial No. 663,386.

To all whom it may concern:

Be it known that I, EMIL SCHÄRER, a citizen of the Swiss Confederation, residing at Steinwiesstrasse 86, Zurich, Switzerland, 5 have invented new and useful Improvements in or Relating to Scaffolding for Buildings and the like, of which the following is a specification.

The object of my invention is to provide 10 a new means of supporting scaffolding for buildings, by use of which upright poles are entirely dispensed with.

By use of the invention scaffolds can be 15 strongly and securely erected in a very short time and entirely from the outside of the buildings. It is of great advantage when used in connection with buildings that abut footways or roads as by the absence of the poles no obstruction is caused.

20 In carrying out my invention I provide a number of sockets which I build into the external walls of a building placing them at regular intervals in vertical and horizontal rows the said sockets being adapted to 25 receive and to sustain the ends of horizontal rails of brackets. The lower ends of the brackets abut against the wall or against brackets situated below and I place on three consecutive brackets arranged in vertical 30 row a main support carrying the platform for the workmen.

In the accompanying drawings one mode of construction is shown by way of an example wherein:

35 Figure 1 shows a vertical section of a wall with a number of superposed brackets carrying one main support secured in position. Fig. 2 shows a part of a staging in a ground plan. Fig. 3 shows the connection of the main support with a bracket in a side elevation and Fig. 4 is a cross section thereof. Fig. 5 shows a bearer for planks in a side view and Fig. 6 in a front view. Fig. 7 is a side view of a socket with the 45 end of the horizontal bar of a bracket inserted therein. Fig. 8 is a front view of the socket. Fig. 9 shows a device for making a cement-socket in a wall in a side view. Fig. 10 is a cross section on line A—B of Fig. 9. Figs. 11 and 12 show a collapsible bracket in two side views. Figs. 13-17 50 show details of construction.

According to my invention I place sockets 1 (Figs. 1, 2, 7 and 8) at suitable levels

and intervals and at right angles with the 55 walls so that their mouths are flush with the walls of the building. Each socket consists of a piece of iron with rectangular cross section. In the front end of the socket is a circular opening 2 having two recesses 3 60 arranged opposite each other. The dimensions of the opening 2 are such that the free end 4 of the bracket with its noses 6 can be easily inserted. The recesses 3 are situated in a horizontal line when the socket 65 1 is correctly placed in the wall and the bracket 5 has to be turned through a right angle when it has to be taken out of the position shown in Fig. 1. The bracket 2 consists of a horizontal bar bent at a right 70 angle at 8 the other end 4 has preferably a round cross section and noses 6 situated opposite each other. The bracket comprises further a bar 5^b rigidly fixed on the horizontal bar and its other end is slightly bent 75 and provided with an eye 7 through which the free end 4 of any bracket may be inserted. To stiffen the bracket a truss 5^a is provided connecting the horizontal bar with the bar 5^b. The free end of the bar 5^b may 80 be provided with a plate 21 (Fig. 1) when the bracket is to be used as the lowest one of a vertical row of brackets.

The free ends 8 of the brackets 5 extend 85 upwardly. On each of the ends 8 an open collar 16 is placed having the form of a C. The free ends of the collars 16 embrace the flanges of a vertical bar 11 of a main support 10. The bar 11 is of T shaped cross section the collars 16 embracing the flanges 90 thereof. In one of the flanges of bar 11 cross pins 15 are fixed by means of which the main support rests on the collars 16 and thereby on the brackets 5. To secure the collars 16 a pin 17 is removably fixed in 95 the end 8 of each collar. To the bar 11 a horizontal bar 12 is rigidly fixed. To stiffen the main support 10 a truss 13 is provided which is rigidly fixed to the bars 11 and 12. To form a platform suitable for executing 100 work ledges 18 are placed on the bars 12 and on said ledges are placed hangers or bearers 19 two of which carry a cross bar 20. On the bars 12 and 20 boards are placed to serve as a stand for the workmen. On 105 the bars 12 uprights may be fixed to serve as a guard for the workmen. To distribute the load on the platform equally on the

three brackets wedges 21 may be used which can be driven between the pins 15 and the collars 16.

By erecting a wall the sockets 1 are built 5 into the wall in vertical rows in such distances apart that a bracket inserted in one socket reaches with its lower end the next lower socket 1 in such a manner that the eye 7 lies exactly over the bore of the socket. 10 Taken for instance that the platform has to be raised to enable the bracket-layers to proceed with their work then a workman will stand on a board laid on the brackets 5. Then he will have to remove the pins 15 15 and lift the main support 10 for a distance which equals the distance for which two sockets 1 are apart. By raising the main support the latter enters a sleeve 16 of an upper bracket. He now fixes the pins 15. 20 It has been found that the bracket would not afford a safe platform for the workmen as the sockets 1 nearest to the workplace are in most cases in brickwork not yet dry, etc. Therefore it will be necessary 25 to distribute the whole load over three or at least two brackets 1.

Instead of having sockets of metal they may be made of cement. I may make a brick of cement or the like having an opening 30 to receive the end of the bracket and I build the brick in the wall at the proper place in the usual manner. If sockets are to be inserted in walls already existing I make a hole in the same and I use a core 35 shown in Figs. 9, 10 to form the opening for the bracket end in a block of cement with which the hole is filled. The core comprises a piece 44 of rectangular cross section and two pieces 42, 43 arranged on both 40 sides of the piece 44. Each of the pieces 42, 43 is provided with a nose. By the construction of a socket a washer 46 is placed over the pieces 42, 43 and 44 and the whole device is placed in the hole of the wall which 45 is then filled up with cement as shown. After a time when the cement has hardened the piece 44 is drawn out and after that the pieces 42, 43. The washer 46 remains in the opening and forms an abutment for the 50 noses of the horizontal bars of the brackets. The mouth of the opening has an enlargement 47 adapted to receive a cover to hide the opening.

As shown in Figs. 11 and 12 the bracket 55 may be made foldable. The horizontal bar 30 is provided with noses 31 for the purpose described above. On to the bar 30 two members 34 and 35 are linked by means of pivots 32 and 33. The members 34, 35 are 60 jointed by means of a pin 36 which is re-

movable in the eyes of the two members 34, 35. The pin is fixed to a chain which is attached to the member 35.

The connection of the member 34 and bar 30 may be made as shown in Figs. 13 and 65 14. The bar 30 is provided with a slot and the member 34 with a cross pin 41 which may pass through the slot. For mounting the bracket the pin 41 is passed through the slot and the member 34 turned through a 70 right angle. The bar 30 rests on the members 34. The end of the bar 30 may be enlarged as shown in Fig. 2 and the opening 75 of the socket adapted to receive the said end is shown at 40 in Fig. 17. The end of the horizontal bar may be bent as shown in Fig. 16 and the hole in the socket would have a corresponding slope. Also I have described the best way of executing my invention I can think of various details of construction 80 can be altered without departing from the spirit of my invention.

What I claim is:

1. The combination with an outside wall of a building, of a plurality of superposed supporting brackets extending outwardly from said wall, a work supporting bracket extending vertically along said supporting bracket, collars for connecting said working bracket with said supporting brackets, and pins supporting said working bracket on said collars, substantially as described. 85

2. The combination with the outside wall of a building, of a plurality of superposed supporting brackets extending outwardly 90 from said wall, said brackets having upwardly projecting ends, ring-like collars adapted to surround and be supported by said ends, a single scaffolding bracket extending vertically along said supporting 95 brackets, and means for securing said scaffolding brackets to said collars. 100

3. The combination with the outside wall of a building, of a plurality of sockets therein arranged in superposed relation, and superposed supporting brackets connected with said sockets at their upper end and having eyes at their lower end, the vertical height of said brackets being equal to the distance between two successive sockets, 105 the eye of one bracket surrounding the next lower bracket at the point at which it engages the corresponding socket. 110

In testimony whereof I affix my signature in presence of two witnesses.

EMIL SCHÄRER.
